UNITED STATES PATENT OFFICE

OSCAR C. FOSTER, OF PICARDSVILLE, ALBERTA, CANADA

HAIR CLIPPER

Application filed August 2, 1928. Serial No. 296,911.

The present invention relates to improvements in hair clippers and has for its principal object to provide an implement that can be positively and efficiently operated in cutting the hair in places which are ordinarily difficult to reach with the type of hair clipper now generally used.

A further object of the invention is to provide a hair clipper, wherein the parts comprising the same may be readily and easily assembled and disassembled for cleaning purposes, the device being further simple in construction, inexpensive, strong and durable, and further well adapted to the purpose for which it is designed.

Other objects of the invention will become apparent as the nature of the invention proceeds, and when taken in connection with the accompanying drawings.

In the accompanying drawing, forming a part of this application and in which like numerals designate like parts throughout the several views:

Figure 1 is a plan view of the hair clipper embodying my invention.

Figure 2 is a longitudinal sectional view therethrough.

Figure 3 is a detail of the operating mechanism for the reciprocating toothed blade, and

Figure 4 is a transverse section taken approximately on the line 4—4 of Figure 1.

In the drawing, wherein for the purpose of illustration is shown the preferred embodiment of my invention, the numeral 1 designates generally my improved hair clipper, the same comprising a straight handle portion 2 that is formed at its forward end with the stationary toothed blade 3. This blade is formed with the cutting teeth 4 in its opposite edges. The handle 2 is cut out in its upper face as at 5, for a purpose to be presently described. Furthermore, the forward end portion of the handle 2 is enlarged, as illustrated at 6.

Adapted for reciprocatory movement on the upper face of the stationary toothed blade 3 is the toothed blade 7, the same being also formed with the cutting teeth at its opposite side edges as shown at 8. The teeth 8 cooperate with the teeth 4, for cutting the hair in the manner well known in the art. This upper cutting blade 7 is formed with a rearwardly extending shank 9 that enters the forward end portion of the housing 10 provided for the open top side of the handle 2, and this housing is removably secured on the handle portion 2, as indicated very clearly in Figure 2. The forward end portion of the housing 10 is provided with an enlargement 11 for disposition over the enlarged portion 6 of the handle 2.

The upper cutter blade 7 is formed with the spaced longitudinally extending slots 12, through which extend the stub bolts 13 that project upwardly from the bottom blade 3 and the stub bolts 13 cooperate with the slots to provide means for the removal of the upper blade 7. A cover strip 14 is disposed over the slot 12 on the upper face of the top blade 7 and this cover strip is formed with openings to accommodate the stub bolts 13. Suitable nuts 15 are threaded on the upper ends of the stub bolts and spring washers 16 are also arranged on the stub bolts for disposition between the nuts 15 and the cover strip 14 as clearly shown in Figure 2. The operating means for the reciprocating upper blade 7 will now be specifically described.

A lever 17 is formed at its inner end with an enlarged head 18, that extends through the upper side of the enlarged portion 6 of the handle 2 and is pivoted as at 19. The portion of the head that projects into the channeled portion 5 of the channel 2 has upwardly extending therefrom the pin that is operable within a transverse recess 21, formed in the bottom face of the inner end portion of the shank 9 and this feature is clearly shown in Figures 2 and 3. A retractile coil spring 22

is arranged between the opposed cut out faces of the handle and the housing 10. The rear end of this spring is secured in this rear end portion of the handle, while the forward end of the retractile coil spring is connected 5 to the eye bolt 23, that is driven into the rear end of the shank 9.

Normally, the parts are arranged as shown in the drawings, and the lever 17 is held outwardly of the adjacent side of the handle of 10 the hair clipper. By pressing inwardly on the lever 17, said lever will swing on its pivot 19 to cause the pin 20 that is in engagement with the recess 21 to force the upper blade 7 15 forwardly along the upper face of the bottom blade 3 against the tension of the coil spring 22, whereby the cutting teeth 4 and 8 will cooperate to cut the hair. By releasing the lever 17, the spring 22 will automatically return 20 the parts to their normal position.

It will thus be seen from the foregoing description that I have provided a hair clipper that will at all times be positive and efficient in its operation, and by reason of its construction, 25 the same can be efficiently used in places for cutting the hair, which are difficult to reach with the ordinary type of hair clipper. Also the construction of my hair clipper is such as to permit the parts to be readily and 30 easily assembled or disassembled for cleaning purposes whenever necessary.

While I have shown the preferred embodiment of my invention, it is to be understood that various changes in the size, shape and arrangement of parts may be resorted to, without departing from the spirit of the invention or the scope of the appended claim.

Having thus described my invention, what I claim as new is:

40. A hair clipper comprising a lower double toothed edged blade having a handle portion formed with a recess on its upper face, an upper double toothed edged blade adapted to slide upon the lower blade and cooperate 45 therewith in properly clipping hair, a shank portion on said upper blade, an eye at the extremity of the shank portion, a transverse slot being formed near the extremity and on the underside of said shank, and the cutting portion of said upper blade being provided with longitudinal bolt receiving slots; 50 a friction plate riding upon said upper blade having bolt receiving holes, bolts through the holes, said plate, and through the slots in 55 said upper blade and secured in the lower blade, spring washers on said bolts and adjusting nuts adapted to confine said spring washers and assemble said plate and blades; 60 a pivoted blade operating handle projecting laterally from this forward part of the handle portion of said lower blade, an enlarged head on the inner end of said handle, a cover plate disposed upon and secured to the handle portion and co-extensive there- 65 with, a pivot placed through said cover plate,

through the enlarged head of the lever and through the lower handle portion; and an upstanding pin on the inner extremity of the enlarged head of the lever for operative engagement in the transverse slot of the upper blade shank; and a contracting spring having one end stretched between the eye on the extremity of the upper blade shank at a point near the rear portion within the casing formed by said cover plate and the handle portion of the lower blade.

In testimony whereof I affix my signature.

OSCAR C. FOSTER.
